(57) **CLAIM**

The ornamental design for a flexible mobile electronic device, as shown and described.

DESCRIPTION

FIG. 1 is a front perspective view of a flexible mobile electronic device according to a first embodiment;

FIG. 2 is a front perspective view thereof shown in a rounded state;

FIG. 3 is a front perspective view thereof shown in an adjusted state;

FIG. 4 is a front perspective view thereof shown in a straight state;

FIG. 5 is a front perspective view thereof shown in a flexed state;

FIG. 6 is a front elevation view in a straight state;

FIG. 7 is a side elevation view thereof, the other side being a mirror image;

FIG. 8 is a back elevation view thereof;

FIG. 9 is a top elevation view thereof;

FIG. 10 is a bottom elevation view thereof; and,

FIG. 11 is a front perspective view of a second embodiment of the flexible mobile electronic device shown in FIGS. 1-10, the only difference over the first embodiment being that the keypad and display are included in the second embodiment.

The broken lines immediately adjacent the shaded areas in the first embodiment represent the bounds of the first embodiment while the circle on the side and all other broken lines are directed to environment and are for illustrative purposes only; the broken lines form no part of the first embodiment.
